E. P. PORTER AND G. W. HALLETT, OF WATERFORD, NEW YORK.

Letters Patent No. 71,411, dated November 26, 1867.

IMPROVEMENT IN DOOR-LOCKS.

The Schedule referred to in these Letters Patent and making part of the same.

TO ALL WHOM IT MAY CONCERN:

Be it known that we, E. P. PORTER and G. W. HALLETT, of Waterford, in the county of Saratoga, and State of New York, have invented new and useful Improvements in Locks; and we do hereby declare that the following is a full, clear, and exact description thereof, which will enable others skilled in the art to make and use the same, reference being had to the accompanying drawings, forming part of this specification.

The present invention relates to a lock, heretofore patented by us on the twenty-sixth day of March, A. D. 1867, which lock embraced a series of four or more catches arranged to engage with the bolt, each and all of which catches have to be thrown back separately by the key in the operation of unlocking, in which position they are retained by suitable spring-catches, when all having been thus thrown back the bolt is free for operation by the key, or, in other words, to be drawn in or thrown or moved out. And this invention consists—

First, in so arranging the said catches, and cam-shaped pieces or "lift-ups," as we intend to denominate them, that if the key, in being moved from one catch to another in the operation of unlocking, be not partially or sufficiently withdrawn for its bit to pass over the said "lift-ups," it will, by passing under them, so raise or lift them as to release the catch or catches previously disengaged from the bolt, that, then flying or swinging back to their original position in contact with the bolt, must again be disengaged therefrom before the bolt can be drawn, whereby, to a person or persons unacquainted with such operation of the lock, even though in possession of a key or keys thereto, much annoyance, hindrance, and trouble will be occasioned, as they must from time to time, before completing the movements requisite to release all the catches, disturb either one or more of the "lift-ups," and thus necessitate a repetition of the operation of releasing the catches to a greater or less extent.

Second, the combination with the catches to the bolt of a series of slides, either more or less in number, so constructed and arranged as to be thrown into such a position, as the key is turned, as will prevent the catches being swung back too far for the spring-catches, which hold them out of contact with the bolt, to properly engage with them therefor.

In the accompanying plate of drawings our improvements in locks are illustrated—

Figure 1 being a view of the interior of the casing to a lock provided with a locking-mechanism, embraced in the Letters Patent hereinbefore referred to, in combination with our improvements constituting this invention.

Figure 2, a transverse section, taken in the plane of the line x x , fig. 1.

Figure 3, a view of the key to the lock.

Similar letters of reference indicate corresponding parts.

A, in the drawings, represents the casing of the lock. B, the bolt thereto, arranged to move within in the lock-casing, and to project, when properly thrown therefrom, through the front or face-plate C to the casing. This bolt B is slotted at D, in the direction and for a portion of its length, by which slot it moves upon the fixed key-pin or spindle E to the back plate of the lock-casing. H H, a series of catches, each hung upon a fulcrum-pin or centre, I, of the lock-casing, two upon each side of the bolt, along and in the same direction with which they extend. These catches H are all of a similar form or shape, which consists in rounding off their ends toward the key-pin E, in an outward direction therefrom, and in forming at their opposite ends a square-shaped shoulder, J, which shoulder-pieces J of the two catches, toward the inner end of the bolt, fit over such end with the shoulder-pieces of the other catches engaged with the shoulders K, formed by the cross-piece L of the bolt, at or near the face-plate to the lock. For the two catches of the lock upon the same side of the bolt, a bent spring, M, is provided, that at its centre is fixed in position to the lock-casing, but at its ends is loose, bearing by them against the catches at or near their shouldered ends. The object of the bent springs is to hold the catches against the bolt, and, when disengaged therefrom by any suitable means, to throw them back into connection with them. Each catch H is provided with a similar tubular-shaped arm, N, through each of which a pin or stud, O, is arranged to play, resting by its lower end against the face of the bolt, where, by means of a bent spring, P, for each pin, each pin is firmly held in such position. Upon each edge or side of the bolt corresponding in position to the pins O in each case, is a similar notch or way, the upper surface of which is inclined from one end to the other, with a shoulder at one end. The upper end of each of the studs O is headed, and by such heads the two studs, upon opposite sides of the bolt, at the same end, are hung in the slotted ends of the

side arms O^2 , to lever P^2 , that by one end are hung so as to swing upward from the bolt, and at their other ends O^2 , project into the plane of movement of the bit to the key, when it is swung around upon the centre-pin, as will be hereinafter described. The under side of the ends O^2 to the levers P^2 , are made of a cam-shape, so that if the key-bit passes under them it will raise or lift them, and thus lift the studs O which they carry, whereas, between their upper faces and the lock-casing, there is a sufficient distance for the bit to pass by, if properly drawn out therefrom. T , pins or studs secured to back plate of lock-casing, which pins act as guards to two of the spring-catches, and not only prevent their being tampered with by inserting any implement in the key-hole of the lock, but also serve to confuse a person if unacquainted with its construction in attempting to unlock it. U U U , guard-pieces in the lock-casing to the two sides of bolt B , for a similar purpose to that of the pins or studs T . V , a lug on bolt against which the bit of the key, shown in fig. 3, is to act for moving or throwing the bolt in or out, as the case may be, when such key is brought to bear against it in the proper direction therefor, provided all the spring-catches have been released from the bolt. X , a spring-catch, secured to the lock-casing in proper position to engage with the lock-bolt, and hold it when thrown out, as well also to be acted upon and depressed by the key when pushed inward, and thus relieved from the bolt previous to its being moved or drawn in by the action of the key against the lug of the bolt.

When the lock is to be locked, the key is first inserted in the key-hole of its casing, and then turned around until it comes against the lug V of the bolt, when, turning the key in the same direction to that in which the bolt is to move, the bolt can be thrown out, and the lock thus locked, in which position, by the spring-catches H , which then interlock therewith, the bolt is held and secured, as has been hereinbefore explained. The catch X also serves to hold it, and with the catches H the bolt cannot be drawn in until they have been one and all released therefrom. In unlocking the lock, the several catches H are released from the bolt, by properly bringing the key to bear against them for turning them on their fulcrum-pins I , where, by the pins O in the ways of the bolt, they are held, when, then, bringing the key against the bolt-lug V , pressing it inward, and at the same time turning it, the catch X is released from the bolt, and the bolt moved and drawn into the lock-casing. In the operation of releasing the catches H from the bolt to unlock it, it is necessary to pass or swing the bit of the key by the ends of the levers P^2 , and if, in passing by them, the bit should move under them, they will be lifted thereby, and thus, as the slides or pins Q are hung to such levers, they will be lifted, leaving the catches H free to swing into position and become engaged with the bolt, whereby, before the bolt can be drawn in, they must again be disengaged, whereas if the bit is drawn out sufficiently to pass over such levers, no action will be produced upon them, and consequently no disturbance of the position of the catches.

A^2 , slides arranged within the lock-casing, one upon the upper and the other upon the lower side of the bolt. These slides are provided with lugs, against which the bit of the key abuts as it is turned with the lock, and thus the said slides moved sufficient for them to prevent the catches H being swung too far, as and for a purpose hereinbefore stated.

We claim as new, and desire to secure by Letters Patent—

The combination, with the catches H , of the levers or "lift-ups" P^2 , or their respective equivalents, when combined together, substantially as and for the purpose described.

We also claim the slides A^2 , either one or more, substantially as and for the purpose specified.

E. P. PORTER,
G. W. HALLETT.
